[57] CLAIM

The ornamental design for a container for coffee additives, as shown and described.

DESCRIPTION

FIG. 1 is a front elevation view of a container for coffee additives showing my new design;
FIG. 2 is a top plan view thereof;
FIG. 3 is a right-hand side elevation thereof;
FIG. 4 is a bottom plan view thereof;
FIG. 5 is a top plan view of the container, with its cover removed; and
FIG. 6 is an exploded perspective view of the container. The rear elevation is identical to FIG. 1, and the left-hand side elevation is identical to FIG. 3.

FIG. 6.

FIG. 2.

FIG. 1.

FIG. 3.

FIG. 4.

FIG. 5.
